UNITED STATES PATENT OFFICE.

LE ROY LINDBERG, OF LANGFORD, SOUTH DAKOTA.

ROTARY SWITCH.

Application filed December 19, 1927. Serial No. 241,182.

My invention pertains to improvements in rotary switches, wherein the same is adapted to be employed for controlling a multiplicity of circuits.

5 The nature of this switch adapts the same particularly for use in conjunction with radio sets employing batteries, wherein the batteries must necessarily be charged after certain intervals of time when they become 10 de-energized.

A more specific purpose of this switch, 15 besides in providing a controlling means in association with a radio outfit, whereby the batteries may be recharged without disconnecting the feed wires to the respective units of the radio apparatus.

The main object of this novel switch device resides in the means whereby the batteries 20 will be connected in series during the use of the radio apparatus, but wherein the connections to the switch may be transferred from series connection with the units of the apparatus, to a hook-up in parallel with the charging source.

25 Other very important objects will be identified from the manner in which these connections are made, as certain advantages in construction, novel in the art.

In the drawing:—

30 Fig. 1 discloses a top plan view of the switch construction in its entirety.

Fig. 2 represents one end elevation of the device.

35 Fig. 3 represents a vertical longitudinal view taken substantially on the line 3—3 of Fig. 1.

Fig. 4 is a base elevation of the inner side of the insulating strip provided with a parallel hookup arrangement.

40 Fig. 5 is a similar elevation disclosing the insulating strip provided with the series hook-up arrangement.

Fig. 6 is a cross sectional view through the rotor, and taken substantially on the line 45 6—6 of Fig. 3, and

Fig. 7 represents a perspective view of one of the cap members.

Now for a more detail description of my invention, I refer to the drawings, in which like numerals designate like parts. The construction of this switch includes a substantially rectangular shaped base 1, having an L-shaped standard 2 arranged upon the base at each end thereof. Suitable binding posts 55 3 are in electrical connection with the standards, the latter being constructed of a con-

ductive material, such for instance, as copper, or the like.

It is preferable that these standard members be connected adjacent one longitudinal edge of the base, to allow a space for the spring fingers to be described fully hereinafter. Each of these L-shaped standards is formed with an opening adjacent its upper end, wherein the respective ends of the rotor 65 generally referred to by the numeral 4 may be journaled for rotation.

The rotor structure includes a pair of caps 5 and 6 of conductive material, the outer surface of each being substantially convex in shape, as clearly disclosed in the drawings. The caps are each provided with outstanding pintles 8 and 7 respectively, which are adapted to project through the openings in the respective standards. The inner face of 75 each of the caps is provided with a pair of outstanding spaced plates 9—9.

The connecting body 10 of the rotor is substantially H-shaped in cross section. The pair of caps 5 and 6 respectively, are adapted for association with the opposite end of the connecting body of the rotor, in a manner whereby the spaced plates 9—9 will engage the opposed surfaces of the web portion 11 at each of its ends respectively. 85

The rotor body is to be constructed of an insulating material, such as porcelain, hard rubber, fiber, or the like.

An elongated strip of insulating material 12 has arranged upon one side thereof, a pair 90 of metallic strips 13 and 14 respectively. This strip is substantially the same length as the rotor body 10, and is adapted for disposition within the rotor body. The outer end portions of the respective strips 13 and 14, are of suitable area, to provide the positive contact against the outer surface of coplanar plates 9—9 of the respective caps. 95

The strip 13 is reduced to a narrow connector 15 which extends a substantial distance along the insulating material to terminate in spaced relation with the enlarged end portion of the plate 14. Along this connector 100 15 at equal spaced intervals, inwardly projecting caps 16 are formed. The conductive strip 14 is likewise shaped, being formed with a reduced connector 17, extending adjacent the opposite longitudinal edge of the insulating material to terminate in spaced relation with the enlarged portion of the 115 strip 13.

The connector 17 is also formed with simi-

lar taps 18, which are equi-distant in spaced relation between the taps of the parallel connector 15. Openings are formed through the strip of insulating material, and through 5 each of the caps 16 and 18 respectively, so that the openings will be arranged substantially in longitudinal spaced relation on the strip 12.

Contact members 19, substantially rectangular in shape, are formed with their outer 10 surfaces longitudinally curved. The arcuate curvature of the outer surface of the respective contact members, is to be substantially of the same diameter as the arcuate 15 outer surfaces of the connecting body. Each of these contact members is provided with a threaded pin 20, which is adapted to extend through the respective openings in the insulating material, to electrically connect 20 through the respective caps 16 and 18.

Nuts 21 are adapted to be threaded on the threaded ends of the pin 20 to secure the respective contact members tightly to the outer surface of the insulating strip, and to 25 positively connect the respective caps therewith.

The second strip of insulating material 22 is provided with a multiplicity of contact members 23 arranged upon one side thereof, 30 each of said contact members being in circumferential alinement with corresponding contact members of the opposed insulating strip. These contacts 23 also have their outer 35 faces arcuate in like manner, and are provided with threaded pins 24, which extend through the strips and project for a substantial distance beyond the opposed sides. Pairs of these contact members are connected together at the opposite side of the insulating 40 strip by conductive connectors 25. While nuts 26 threadable upon the threaded pin are employed for assuring a positive electrical connection with the contact members.

In this manner, the strip 22 provides a 45 group of series connections, the purpose of which will be further described, hereinafter. A bolt 27, is employed at each end of the rotor, for securing the insulating strip within the rotor body. Spaced from the rotor 4 and in adjacent parallelism with one longitudinal edge of the base 1, a plurality of 50 spring contact fingers 28 have one of their end portions secured between the strip of insulating material 29 and 30 respectively, 55 these spring fingers being complementary to each circumferentially alined pair of contact members on the rotor, while the opposite edge portions of each of said fingers is secured between the respective insulating strips 29 and 30, in a manner to allow its 60 ends 31 to project a slight distance beyond.

Bolts 32 pass through the respective in-

sulating strips, and base, while the nut 33 may be threaded on the bolt for tightly binding the elements together. These bolts are 65 arranged at spaced intervals, and between the strips in a manner clearly shown in Fig. 1 of the drawing.

A to F inclusive, represent the positive and negative connections of the batteries, to 70 the strip. When it is desired to employ this switch in conjunction with the radio apparatus, the handle 34 may be oscillated to bring the series contact members 23 into contact with the fingers 28. In this manner, the batteries will have their poles connected in 75 series with the various units of the radio apparatus. However, when it is desired to charge the batteries, the charging source of current may be connected with the binding post 3. 80

The handle 4 may then be oscillated, so as to bring the contact members 19 into contact engagement with the fingers 28. The charging currents will then pass thru the respective standards 2, the clamps 5—5, and through 85 the respective strips 13 and 14, of the insulating strip 12. The parallel arrangement of the contact members 19, by reason of the connectors 15 and 17 respectively, will change the hook-up arrangement with the spring 90 arms 28 from a series connection to a parallel connection, simultaneously setting on the charging current.

It will now be seen that I have provided a very novel switch device, which will allow 95 the uninterrupted service of the radio apparatus, while providing a ready means whereby the batteries employed in conjunction with the apparatus may be recharged without disconnecting any of the connections. This will 100 eliminate loose connections to the battery, as these connections may be soldered to the battery terminal, which heretofore has been impossible due to the fact, that these connections must be broken in order to recharge the batteries. 105

Having thus described my invention, what I claim as new is:—

In a switch of the character described comprising a base, a pair of spaced supports on the base, a rotor journaled between said supports, said rotor being formed with a pair of spaced longitudinal channels, a strip of insulating material arranged in each of said channels, one of said strips being provided 110 with a plurality of contacts connected in electrical parallelism, the other strip being provided with a plurality of contacts connected in pairs, and a plurality of spring arms supported on the base and adapted to engage 115 with the contacts. 120

In testimony whereof I affix my signature.

LE ROY LINDBERG.
